INVENTOR

Charles P. Oudin,
by E. E. Masson, Attorney.

UNITED STATES PATENT OFFICE.

CHARLES P. OUDIN, OF SPOKANE, WASHINGTON.

HOLLOW-TILE GIRDER AND WALL.

SPECIFICATION forming part of Letters Patent No. 511,249, dated December 19, 1893.

Application filed September 20, 1893. Serial No. 485,990. (No model.)

To all whom it may concern:

Be it known that I, CHARLES P. OUDIN, a citizen of the United States, residing at Spokane, in the county of Spokane, State of Washington, have invented certain new and useful Improvements in Hollow-Tile Girders and Walls, of which the following is a specification, reference being had therein to the accompanying drawings.

- 10 My invention has reference to the construction of fire proof floors, ceilings and partitions of buildings; and the objects of my improvement are to obtain in said constructions, lightness with great strength and permanency 15 of the structure, by interlocking the tiles out of which it is made on lines adjacent to both their flat faces. I attain these objects by the construction illustrated in the accompanying drawings in which—
- 20 Figure 1 is a perspective view of a portion of a flat arch constructed in accordance with my invention. Fig. 2 is an end view of two of the tiles provided with interlocking grooves and ribs adjacent to both of their flat faces, 25 and united together in accordance with my invention. Fig. 3 is a perspective view of a partition-tile having also ribs and grooves adjacent to both of its flat faces in accordance with my invention.
- 30 In said drawings A represents an I beam of metal, against the sides of which are placed the skewback bricks C, and against the latter the hollow tiles B. Two of the sides of said tiles are made flat as shown at b, and when 35 used in the construction of an arch the upper flat surface constitutes the floor of a room, while the under flat surface constitutes the ceiling of the room under it. The two other sides of each tile have a hollow recess b² formed therein preferably in the form of a half cylinder, and above and under said recess, flat faces b³ b⁴, are provided to serve as 40 abutments for each tile to bear against the adjacent tile. But to prevent any of the tiles 45 of a floor from occupying either an elevated or a depressed position relatively to the tiles placed on the sides thereof, each tile has formed in one of its sides, grooves b⁵ and in the opposite side is provided with semi-cylindrical ribs b⁶ between the abutments b³ b⁴ and close to the flat faces b. The grooves b⁵ and

ribs b⁶ are made of such size as to firmly interlock and form a side support for each other; while they are retained endwise by having their slightly beveled ends pressing 55 against the skewback bricks.

The advantages obtained by having the two interlocking grooves and ribs b⁵ b⁶ as far from each other as possible, viz: close to the flat faces b, in place of in the center between 60 said faces, are that, the tiles cannot rock on their centers, and thus greater stability is obtained. By this construction even if one of the ribs of the pair is damaged the tile will still be properly retained by the other rib 65 and groove. The large central recesses b² in the sides of the tiles constitute, (when two of the tiles are laid against each other,) arched chambers well adapted for the passage of tie bolts d that may be used to unite the I beams 70 of the floor. The top and bottom flat faces b are united together between their ends by strengthening partitions b⁷ abutting on the arched walls of the chambers b².

The partition tile shown standing in Fig. 3 75 is also provided with two interlocking grooves b⁵ and ribs b⁶ in two of its sides adjacent to its flat faces b, and the latter are united together by partitions suitably located between them.

Having now fully described my invention, I claim—

1. Two hollow tiles having two flat faces b, and in each side two interlocking ribs and grooves alongside of said faces and an arched chamber b² between the ribs and grooves in either side of the tile substantially as described.
2. The combination of an I shaped beam A, skewback bricks alongside thereof, a hollow tile having two flat faces b, an arched chamber b², and two abutments b³ and b⁴ in the sides, with two grooves b⁵ in one side, and two ribs b⁶ in the other side, each groove and rib being close to the flat faces b substantially as described.

In testimony whereof I affix my signature in presence of two witnesses.

CHARLES P. OUDIN.
